UNITED STATES PATENT OFFICE

167,004

STOCKING

Stanton D. Sanson, Elkins Park, Pa., assignor to Sanson Hosiery Mills, Inc., Philadelphia, Pa.,
a corporation of Delaware

Application December 8, 1951, Serial No. 17,672

Term of patent 14 years

(Cl. D47—7)

To all whom it may concern:

Be it known that I, Stanton D. Sanson, a citizen of the United States and a resident of Elkins Park, county of Montgomery, State of Pennsylvania, have invented a new, original, and ornamental Design for Stocking, of which the following is a specification, reference being had to the accompanying drawings, forming a part thereof, wherein:

Figure 1 is a rear perspective view of the lower portion of the stocking showing my new design; and

I claim:

The ornamental design for a stocking, as shown.

STANTON D. SANSON.
